A. GERTSFELD

LOCK

Filed May 6, 1924

Inventor

5 Abraham Gertsfeld
By his Attorney

Harry Radzinaty

UNITED STATES PATENT OFFICE.

ABRAHAM GERTSFELD, OF NEW YORK, N. Y.

LOCK.

Application filed May 6, 1924. Serial No. 711,324.

To all whom it may concern:

Be it known that I, ABRAHAM GERTSFELD, a citizen of the United States, and resident of the city of New York, in the county of the Bronx and State of New York, have invented certain new and useful Improvements in Locks, of which the following is a specification.

This invention relates to a door lock, or 10 a lock suitable for other uses, and has for its object to provide a device of this character which will be of strong and sturdy construction, and which will be so made as to prevent it from readily being broken 15 open.

Reference is to be had to the accompanying drawing, forming a part hereof, in which—

Figure 1 is a rear elevation of a lock made 20 in accordance with my invention, parts being shown in section, and the rear cover plate being removed, to disclose the interior construction of the lock;

Figure 2 is a longitudinal cross sectional view, showing the complete lock and the keeper therefor, as the same appear when attached to a door and door frame, respectively, and

Figure 3 is a view, showing the manner 30 in which the interior mechanism of the lock acts to shift the bolts.

Throughout the various views of the drawing, similar reference characters designate similar parts.

35 In the preferred embodiment of my invention, as disclosed in the accompanying drawing, I provide a lock casing 1 which contains the lock mechanism. This casing 1 is provided with the customary edge flange 40. From one of the ends of the casing is provided an extension or projection 33, which is preferably integrally formed with the casing, and this extension is provided with a pair of laterally projecting portions 45 or wings 34 and 35 which form an integral part of the extension. The casing extension thus provided, consisting of the parts 33, 34 and 35, is generally T-shaped and when the lock is closed said T-shaped part is arranged 50 to lie in a corresponding opening in the lock-keeper 9 which is secured to the door frame 40, as will be hereinafter set forth.

55 The keeper 9 consists of angle plate which fits over and is secured to the door frame, a portion of which is indicated at 40, and said keeper is provided with a box portion

or frame having a wall 2, ends 3 and 4 and inwardly extending portions 5 and 6.

A continuous wall composed of the parts 2, 3, 4, 5 and 6 is provided which conforms 60 to and accommodates the T-shaped extension on the lock casing and bolt holes 7 and 8 extend through the portions or walls of the keeper which lie on opposite sides of the wings 34 and 35 of the T-shaped extension. 65

The wings 34 and 35 are provided with corresponding bolt openings so that when the extension lies within the keeper, its bolt openings are in alignment with the bolt 70 openings 7 and 8 in the keeper so that bolts 12 and 13 when projected out of the casing pass through the bolt openings in the extension 33 and also through the bolt openings 7 and 8 in the keeper. 75

The bolts 12 and 13 are secured to, or form an integral part of a plate 11 which is located within the casing and is movable therein to draw said bolts within the casing or shift the same out of the casing and 80 through the respective bolt openings in the casing extension 33 and in the keeper.

The plate 11 is provided with a slot 16 extending longitudinally and a guide pin or stud 17 projects from the inner face of 85 the casing and into said slot and restricts the movement of the plate 11.

At 21 is shown a tumbler plate or locking plate which is provided with an ear or lug 23 pivoted on a stud 24 projecting from the 90 casing. This plate 21 is provided with an elongated slot 25 which extends longitudinally of the plate, and extending laterally from the ends of said slot 25 are slots 26 and 27 in which a stud 28 projecting from 95 the plate 11 is adapted to fit.

A flat spring 29 projects from the upper edge of the plate 21 and bears against the upper flange 10 of the casing.

For the purpose of shifting the plate 11, 100 I provide the usual manually operated knob 32 which projects from the inner side of the lock and is secured to a boss 18 within the casing from which extends a finger 19.

The plate 11 is cut away as at 14 to provide a converging groove in which the finger 19 operates and the end of said groove 14 terminates in a slot 15. When the lock is in its closed position, it will be seen that the bolts 12 and 13 are projected out of the casing and they pass through the bolt openings 7 and 8 in the walls of the keeper and they 110

also extend through the openings provided for them in the extensions 34 and 35 on the casing projection. To withdraw said bolts 12 and 13 within the casing to open the lock, the knob 32 is rotated, swinging the finger 19 as shown in Figure 3, which causes it to ride on the curved underface 22 of the tumbler plate 21, lifting said plate against the tension of its spring 29 and raising the lateral slot 27 from off of the stud 28 on the plate 11.

As the knob 32 is rotated further, the end of the finger 19 enters the slot 15 in the plate 11 and shifts said plate, and during such shifting movement, the stud 28 is moved along through the longitudinal slot 25 (see Figure 3) and this continues until the bolts 12 and 13 are drawn into the casing so that the door 39 may be swung open.

When the bolts reach the limit of their inward movement, the stop 17 has reached the end of its guide-slot 16 and the finger 19 has moved out of the slot 15 and has ceased its lifting movement of the plate 21, permitting said plate to descend under the pressure of the spring 29 so that its lateral slot 26 rests over the stud 28, holding the bolts within the casing and the lock in its open position.

The above describes the manner in which the lock is manually operated from the inside and the same is operated similarly from the outside by a key which enters the ordinary key lock 36 located on the opposite side of the door 39. This lock 36 is held in place by suitable screws 37 which extend through a reinforcing plate 38 on the back face of the door within the lock casing. The key lock 36 when operated by its key rotates a stem 20 which projects into the boss 18 on which the operating finger 19 is formed.

In Figure 1 I have shown the closure plate 32 removed for the purpose of disclosing the lock mechanism. Said plate 32 is shown in Figure 2 where it will be seen that the same is held in place, closing the back of the casing and confining the mechanism in the casing, by means of screws which enter into studs 30 and 31 provided in the casing for their reception.

It will be seen from the foregoing that the construction of my improved lock is such, with its bolts 12 and 13 projecting through the keeper and through the casing extension that it is impossible to insert a tool or other article under the ends of said bolts to thrust the same back and surreptitiously open the lock.

From the foregoing, it is obvious that my invention is not to be restricted to the exact embodiment shown, but is broad enough to

cover all structures coming within the scope of the annexed claims.

What I claim is:

1. A lock having a pair of bolts, an extension projecting from the lock between the bolts, said extension having lateral projections at its end extending in front of the bolts and provided with bolt openings through which said bolts may project, a keeper having portions adapted to lie on both sides of said lateral portions of the lock and having portions adapted to extend around the ends thereof, said keeper being provided with bolt openings located on both sides of said lateral portions, said bolt openings being located in alignment with the bolt openings in said lateral portions and adapted to receive the bolts when the same are projected out of the lock. 65
